UNITED STATES PATENT OFFICE.

JOHN M. SAILER, OF JANEVILLE, WISCONSIN.

DRIVING-GEAR MECHANISM.

1,044,579.

Specification of Letters Patent.

Patented Nov. 19, 1912.

Original application filed July 15, 1910, Serial No. 572,157. Divided and this application filed November 28, 1910. Serial No. 594,496.

To all whom it may concern:

Be it known that I, JOHN M. SAILER, a citizen of the United States, residing at Janesville, Wisconsin, have invented certain new and useful Improvements in Driving-Gear Mechanism, of which the following is a specification.

This invention relates to improvements in driving gear mechanisms.

10 My improved driving gear mechanism is especially designed by me for use in my improved traction engine, for which I filed application for Letters Patent July 15, 1910, Ser. No. 572,157, and this application is a division thereof. My improved driving gear mechanism is, however, adapted for use in other relations.

20 The main objects of this invention are to provide an improved driving mechanism or transmission gearing that is strong, simple and durable, whereby a number of speeds may be secured.

25 A further object is to provide an improved driving mechanism or transmission gearing by which the traction wheels may be driven independently, either in the same or in reverse directions, or whereby power may be delivered to one and not to the other.

30 Further objects, and objects relating to structural details, will definitely appear from the detailed description to follow.

I accomplish the objects of my invention by the devices and means described in the following specification.

35 The invention is clearly defined and pointed out in the claims.

A structure, which is a preferred embodiment of my invention, is clearly illustrated in the accompanying drawing, forming a 40 part of this specification, in which:

Figure I is a detail plan of a structure embodying the features of my invention, the engine proper being omitted and only the crank shaft being shown, and a portion of the frame being broken away. Most of the control levers are also omitted. Fig. II is an enlarged detail longitudinal section taken on a line corresponding to line 2—2 of Fig. I. Fig. III is a detail vertical section 50 taken on a line corresponding to line 3—3 of Fig. II.

In the drawings, similar reference characters refer to similar parts throughout the several views, and the sectional views are taken looking in the direction of the little arrows at the ends of the section lines.

Referring to the drawing, the frame 1 is shown largely in conventional form, as its structural details form no part of the present invention. It will be understood that in practice, the frame will be made of pieces suitably connected. The engine proper or motor, as stated, is not here illustrated.

The traction wheels 2 are also shown in conventional form. They are preferably of the construction shown in my before mentioned application. The axle for the traction wheels 2 is formed of sections 3 and 4, each section being provided with bearings 5 and 6. On the driving or motor shaft 7 is a pair of pinions 8 and 9, which may be secured to the shaft by the clutches 10. These clutches 10 are preferably of the construction shown in my application for Letters Patent filed May 10, 1910, Ser. No. 560,404. The levers for actuating these clutches are not here illustrated.

On the axle section 3 are gears 11, 12, and 13, all of the same size. The gear 13 is fixed to the axle to revolve therewith by means of the key 14, while the gears 11 and 12 are revolubly mounted on the axle and arranged in mesh with the pinions 8 and 9, respectively, on the driving shaft. Pinions 15 and 16 are fixed to the gears 11 and 12, respectively.

Arranged parallel with the axle is a transmission shaft 17. Fixed to this shaft to revolve therewith is a gear 18 meshing with the pinion 15. Revolubly mounted on this transmission shaft 17 is a gear 19, meshing with the pinion 16. Fixed to this gear to revolve therewith is a pinion 20 meshing with the gear 13 on the axle section 3. A clutch 21 is provided for securing the gear 11 to the axle section 3. When this clutch is in engagement, the axle section 3 is driven in a reverse direction. The shifting means for this clutch 21 are not here illustrated.

On the axle section 4 is a gear 22, arranged in mesh with a pinion 23 on the transmission shaft 17. The gears and

pinions are of such dimensions that both axle sections are driven at the same speed, the section 3 being driven for one speed through the train of gears 9, 12, 16, 19, 20 and 5, while the other is driven through the train of gears 8, 11, 15, 18, 23 and 22. With this connection, the axle sections may be driven independently or simultaneously through manipulation of the clutches 10. 10 This is of advantage in steering the engine.

The section 3 can be driven in a reverse direction by means of the clutch 21, as described, while the section 4 is driven in a reverse direction through the auxiliary transmission shaft 24, which is connected to the main transmission shaft through the pinions 25 thereon and the pinion 26 on the auxiliary transmission shaft, and through the pinion 27 to the gear 22.

20 The pinions 23 and 27 are secured to their respective shafts by clutches which are adapted to be manipulated to disconnect both, or connect either of said pinions, a double yoke 28 being provided to engage the shaft members of the clutch, the yoke being operated through the post 29, which is extended into convenient reach of the operator.

To provide another speed, I mount on the 30 transmission shaft a gear 30 having a clutch connection therewith. The means for engaging the clutch members 31 for this gear are not illustrated. I secure to this gear a drum or windlass 32. Revolubly mounted 35 on the axle section 4 is a gear 33, having a hub-like clutch member 34 thereon, and a clutch member 35 arranged within the member 34, see Fig. II. The gear 33 is adapted to be shifted longitudinally to throw the 40 clutches into engagement.

Splined to the axle sections 3 and 4 are clutch members 36 and 37 adapted to coact with the clutch members 34 and 35, respectively, of the gear 33. These clutch members are held yieldingly in position by springs 38 carried by the collars 39 and 40, so that the clutches are permitted a ratchet action. The collar 40 is adapted to receive one end of both axle sections, and also serves 50 as a bearing and support for the axle sections and clutch member 34.

By this arrangement of parts, when the engine is driven through the gears 30 and 33, the axle sections are driven as a continuous axle. At the same time, in turning, a variable speed is permitted through the rigid connection described. The drum 32, through this connection, may be driven independently or simultaneously with the axle. 60 The advantage of this construction is that should the wheels strike soft or slippery ground, the rope 41 may be attached to some fixed object and the engine thus assisted, or the windlass may be used for various purposes 65 when running free from the axle, as,

for example, when the engine is used in hauling hay, the windlass may be used for hoisting it, or for lifting bags of grain onto a wagon or the like.

To assist in controlling the engine, I provide the traction wheels, with independent brakes. These consist of the brake wheels 42, having brake bands 43 thereon. These bands are controlled by the levers 44, which are pivoted to the frame at 45, and provided 75 with laterally-projecting arms or levers 46 arranged so that both may be engaged at the same time, or either of them engaged.

By this arrangement of parts, I secure a transmission that is strong, simple and durable, and provide different speeds, and drive the wheels independently of each other in the same or in opposite directions, or one wheel may be driven and the other permitted to remain neutral so that short turns 85 may be readily effected, or, in case one wheel should strike very soft ground, the other being on better ground, the power may be delivered to the wheel on firm ground. Also, the drum may be driven either in connection with, or independently of the axles, 90 as desired.

I have illustrated and described my improved driving gear mechanism in detail in a practical embodiment thereof. I have 95 not, however, attempted to illustrate or describe the various modifications in structure possible, as I believe these will be readily understood by those skilled in the art to which this invention relates.

Having thus described my invention, what I claim as new and desire to secure by Letters Patent, is:

1. In a structure of the class described, the combination of the driving shaft; an 105 axle formed of sections; a main transmission shaft; a pair of pinions having clutch connections with said driving shaft; gears on one of said axle sections, one of said gears being fixed thereto, and a pair of said 110 gears being revolubly mounted thereon and meshing with said driving shaft pinions, one of said revolubly mounted gears having a clutch connection with said axle sections, said revolubly mounted gears having pinions fixed thereto; gears on said main transmission shaft meshing with said last named pinions; a gear meshing with said gear on said axle section having the clutch connection therewith being fixed to said transmission shaft, the other being revolubly mounted thereon and having a pinion fixed thereto meshing with said gear fixed to said axle section; a gear fixed to the other axle section; a pinion having a clutch connection 115 with said transmission shaft meshing with said gear on said second axle section; an auxiliary transmission shaft geared to said main transmission shaft and a pinion in clutch connection therewith, meshing with 120 said gear on said second axle section; an auxiliary transmission shaft geared to said main transmission shaft and a pinion in clutch connection therewith, meshing with 125 said gear on said second axle section; an auxiliary transmission shaft geared to said main transmission shaft and a pinion in clutch connection therewith, meshing with 130 said gear on said second axle section; an auxiliary transmission shaft geared to said main transmission shaft and a pinion in clutch connection therewith, meshing with

said gear on said second axle section; a drum on said transmission shaft having a clutch connection therewith, said drum being provided with a gear; and a gear having a ratchet clutch connection with both of said axle sections, meshing with said gear on said drum.

2. In a structure of the class described, the combination of the driving shaft; an axle formed of sections; a main transmission shaft; a pair of pinions having clutch connections with said driving shaft; gears on one of said axle sections, one of said gears being fixed thereto, and a pair of said gears being revolubly mounted thereon and meshing with said driving shaft pinions, said revolubly mounted gears having pinions fixed thereto; gears on said main transmission shaft meshing with said last named pinions, one of said gears being fixed to said transmission shaft, the other being revolubly mounted thereon and having a pinion fixed thereto meshing with said gear fixed to said axle section; a gear fixed to the other axle section; a pinion having a clutch connection with said transmission shaft meshing with said gear on said second axle section; a drum on said transmission shaft having a clutch connection therewith, said drum being provided with a gear; and a gear having a ratchet clutch connection with both of said axle sections, meshing with said gear on said drum.

3. In a structure of the class described, the combination of the driving shaft; an axle formed of sections; a transmission shaft; a pair of pinions having clutch connections with said driving shaft; gears on one of said axle sections, one of said gears being fixed thereto, and a pair of said gears being revolubly mounted thereon and meshing with said driving shaft pinions, one of said revolubly mounted gears having a clutch connection with said axle sections, said revolubly mounted gears having pinions fixed thereto; gears on said transmission shaft meshing with said last named pinions, a gear meshing with said gear on said axle section having the clutch connection therewith being fixed to said transmission shaft, the other being revolubly mounted thereon and having a pinion fixed thereto meshing with said gear fixed to said axle section; a gear fixed to the other axle section; a pinion having a clutch connection with said transmission shaft meshing with said gear on said second axle section; a drum on said transmission shaft having a clutch connection therewith, said drum being provided with a gear; and a gear having a ratchet clutch connection with both of

said axle sections, meshing with said gear on said drum.

4. In a structure of the class described, the combination of the driving shaft; an axle formed of sections; a transmission shaft; a pair of pinions having clutch connections with said driving shaft; gears on one of said axle sections, one of said gears being fixed thereto, and a pair of said gears being revolubly mounted thereon and meshing with said driving shaft pinions, said revolubly mounted gears having pinions fixed thereto, gears on said transmission shaft meshing with said last named pinions, one of said gears being fixed to said transmission shaft, the other being revolubly mounted thereon and having a pinion fixed thereto meshing with said gear fixed to said axle section; a gear fixed to the other axle section; a pinion having a clutch connection with said transmission shaft meshing with said gear on said second axle section; a drum on said transmission shaft having a clutch connection therewith, said drum being provided with a gear; and a gear having a ratchet clutch connection with both of said axle sections, meshing with said gear on said drum.

5. In a structure of the class described, the combination of the driving shaft; an axle formed of sections; a main transmission shaft; a pair of pinions having clutch connections with said driving shaft; gears on one of said axle sections, one of said gears being fixed thereto, and a pair of said gears being revolubly mounted thereon and meshing with said driving shaft pinions, one of said revolubly mounted gears having a clutch connection with said axle sections; said revolubly mounted gears having pinions fixed thereto; gears on said main transmission shaft meshing with said last named pinions, the gear meshing with the pinion having a clutch connection with the axle sections being fixed to said transmission shaft, the other being revolubly mounted thereon and having a pinion fixed thereto meshing with said gear fixed to said axle section; a gear fixed to the other axle section; a pinion having a clutch connection with said transmission shaft meshing with said gear on said second axle section; and an auxiliary transmission shaft geared to said main transmission shaft and a pinion in clutch connection therewith, meshing with said gear on said second axle section.

6. In a structure of the class described, the combination of the driving shaft; an axle formed of sections; a main transmission shaft; a pair of pinions having clutch connections with said driving shaft; gears on one of said axle sections, one of said gears being fixed thereto, and a pair of said gears being revolubly mounted thereon and meshing with said driving shaft pinions, said revolubly mounted gears having pinions

- fixed thereto; gears on said main transmission shaft meshing with said last named pinions, one of said gears being fixed to said transmission shaft, the other being revolvably mounted thereon and a pinion fixed thereto meshing with said gear fixed to said axle section; a gear fixed to the other axle section; a pinion having a clutch connection with said transmission shaft meshing with said gear on said second axle section; and an auxiliary transmission shaft geared to said transmission shaft and a pinion in clutch connection therewith, meshing with said gear on said second axle section.
7. In a structure of the class described, the combination of the driving shaft; an axle formed of sections; a transmission shaft; a pair of pinions having clutch connections with said driving shaft; gears on one of said axle sections; one of said gears being fixed thereto, and a pair of said gears being revolvably mounted thereon and meshing with said driving shaft pinions, one of said revolvably mounted gears having a clutch connection with said axle sections, said revolvably mounted gears having pinions fixed thereto; gears on said transmission shaft meshing with said last named pinions, the gear meshing with said gear on said axle section having the clutch connection therewith being fixed to said transmission shaft, the other being revolvably mounted thereon and having a pinion fixed thereto meshing with said gear fixed to said axle section; a gear fixed to the other axle section; and a pinion having a clutch connection with said transmission shaft meshing with said gear on said second axle section.
8. In a structure of the class described, the combination of the driving shaft; an axle formed of sections; a transmission shaft; a pair of pinions having clutch connections with said driving shaft; gears on one of said axle sections, one of said gears being fixed thereto, and a pair of said gears being revolvably mounted thereon and meshing with said driving shaft pinions, said revolvably mounted gears having pinions fixed thereto; gears on said transmission shaft meshing with said last named pinions, one of said gears being fixed to said transmission shaft, the other being revolvably mounted thereon and having a pinion fixed thereto meshing with said gear fixed to said axle section; a gear fixed to the other axle section; and a pinion having a clutch connection with said transmission shaft meshing with said gear on said second axle section.
9. In a structure of the class described, the combination of the driving shaft; an axle formed of sections; a transmission shaft; driving connections from said driving shaft to one of said axle sections including a clutch connection to the axle; driving such axle section to said transmission shaft; reversible driving connections from said transmission shaft to the other axle section; a drum on said transmission shaft having a clutch connection therewith, said drum being provided with a gear; and a gear having a clutch connection with both of said axle sections, meshing with said gear on said drum.
10. In a structure of the class described, the combination of the driving shaft; an axle formed of sections; a transmission shaft; driving connections from said driving shaft to one of said axle sections and from such axle section to said transmission shaft; and reversible driving connections for said transmission shaft to the other axle section.
11. In a structure of the class described, the combination of the driving shaft; an axle formed of sections; a transmission shaft; driving connections from said driving shaft to one of said axle sections; driving connections from said transmission shaft to the other axle section; a drum on said transmission shaft having a clutch connection therewith, said drum being provided with a gear; and a gear having a clutch connection with both of said axle sections, meshing with said gear on said drum.
12. In a structure of the class described, the combination of the driving shaft; an axle formed of sections; a transmission shaft; driving connections from said driving shaft to one of said axle sections; and driving connections from said transmission shaft to the other axle section.
13. In a structure of the class described, the combination of the driving shaft; an axle; a drum; and driving connections from said driving shaft and axle to said drum whereby said axle and drum may be driven independently or simultaneously.
14. In a structure of the class described, the combination, of a sectional axle; a driving connection for said axle sections comprising a gear revolvably mounted on one of said axle sections having a pair of ratchet clutch members thereon, one of said clutch members being hub-like in form and projecting over the end of the other axle section; a pair of coacting ratchet clutch members splined to said axle sections; collars on said axle sections; and springs carried by said collars arranged to engage said ratchet members splined to said axle sections whereby the ratchet action of said clutch connection is permitted when the clutch members are in engagement.
15. In a structure of the class described, the combination of the driving shaft; an axle formed of sections; a transmission shaft; driving connections from said driving shaft to one of said axle sections including a clutch connection to the axle; driving

connections from said driving shaft to said transmission shaft; driving connections from said transmission shaft to said axle section; and reversible driving connections from said transmission shaft to the other axle section.

In witness whereof, I have hereunto set

my hand and seal in the presence of two witnesses.

JOHN M. SAILER. [L.S.]
